UNITED STATES PATENT OFFICE.

SOREN ROBERTSON, OF CLEVELAND, OHIO, ASSIGNOR OF ONE-HALF TO
AZARIAH EVERETT, OF SAME PLACE.

CAR-COUPING.

SPECIFICATION forming part of Letters Patent No. 443,921, dated December 30, 1890.

Application filed September 5, 1890. Serial No. 364,011. (No model.)

To all whom it may concern:

Be it known that I, SOREN ROBERTSON, a citizen of the United States, residing at Cleveland, in the county of Cuyahoga and State of Ohio, have invented certain new and useful Improvements in Car-Couplers; and I do hereby declare that the following is a full, clear, and exact description of the invention, which will enable others skilled in the art to which it appertains to make and use the same.

My invention relates to car-couplings, and may be used in coupling cars of all kinds, but is more especially designed as a coupling for street-cars.

The invention consists of a sectional coupler, in which each section is a duplicate of the other and adapted to be used on reverse ends of the car, substantially as shown and described, and particularly pointed out in the claims.

In the accompanying drawings, Figure 1 is a side elevation of the two sections of the couplings shown as they appear when united, the section at the left hand being broken away in the body to get the same within the limits of the drawings. Fig. 2 is an enlarged longitudinal section of the central portion of the coupling, showing the relation and position of the parts when united, the locking-sleeve 30 at the right being in position to release the bolt, the bolt being unlocked while the sleeve is in that position. Fig. 3 is an end view of one of the sections, showing the sleeve in the same position as the sleeve at the right in Fig. 2, which has just been described. Fig. 4 is a detail of one of the locking-bolts. Fig. 5 is a detail of the inner end of one of the coupling-sections, showing the head thereon and the slot at the side of the bottom. Fig. 6 is a longitudinal section of one of the relief-springs and the box and mechanism connected therewith, as hereinafter described. Fig. 7 is a plan view of the box containing the relief-spring through which the coupling is fastened 45 to the car.

The coupling device here shown and described is made, preferably, about three feet long in each section, or, say, six feet total length, and is designed to be attached to the car-truck instead of the car-body. It may of

course be made shorter and connected only with the car-body, but this is not a desirable way of connecting. Two prime objects were had in view in the construction of this coupling and are obtained therefrom—viz., readiness and simplicity in coupling and uncoupling and the production of a perfect union when coupling has been effected, and, secondly, spring-relief mechanism, whereby the sudden jars in starting and stopping the cars are taken off the trail-car. These results are accomplished by the construction shown, which consists of two duplicate sections A and B, which are alike in every particular, so that a description of one answers also as a description of the other. Thus we have first a tubular bar 10, of suitable length and provided with a longitudinal slot 11, which in operation preferably is on the bottom of the bar, and a head having two heavy annular rings 12 and 13, integral with the bar and having such strength as makes them sufficient to take the strain of the coupling. The rings 12 and 13, which form the head of the bar, extend around substantially to the slot 11 on either side. These rings are placed a suitable distance apart, and the intervening space is occupied by the locking-sleeve 14. This sleeve is made with two sections connected at the center by screws fastened through the ears 15, so that they are removable when occasion requires. This sleeve is provided on one side with a U-shaped extension 16, and upon the opposite side with a weight 17, and is free to turn upon its bearing, so that when in use the weight 85 will by its own gravity drop to the bottom and thus lock the bolt when in that position. A bolt 18 is placed in the tube or bar 10, and has such length that when it is projected, as in locking position, one-half the bolt will 90 rest in each section of the coupling, so as to make practically a rigid coupling or one that will not sag and rattle, and at the same time leave the coupling free to be speedily and easily coupled or uncoupled. The bolt slides back 95 and forth within certain limits in the tube in which it is supported, and has two locking-catches 19 and 20. The catch 19 has such depth that it will not pass through the U-shaped portion 16 of the locking-sleeve when 100

the same is turned opposite the slot 11, as seen in Fig. 3; but when in this position the catch 20 is designed to pass through said sleeve and loop and into position to be engaged by the locking-sleeve 14 of the opposite section. Thus, referring to Fig. 2, it will be seen that the catch or lug 19 has such depth outside of the tube that it cannot pass through the U-shaped opening 16; but the bolt in the 10 left-hand section of the coupling that has been projected through into the right-hand coupling and the catch or lug 20 is in position to be locked when the locking-sleeve 14 turns on its axis and the weight 17 comes to the 15 bottom. Then coupling is effected and the two sections are united for operation. Both sections, as before stated, are made exactly alike, so that if the bolt shown in Fig. 2 were withdrawn, as is the bolt in the right-hand section 20 in Fig. 1, the bolt in said right-hand section could be projected into the left-hand section and the parts would be locked together there just the same as they would be as shown in Fig. 2. This projection is made so that cars 25 made be coupled at opposite ends with equal facility without reversing the car. When two members are brought together, it is immaterial which bolt is used—it may be the bolt of one section or the bolt of the opposite section, and thus also an idle-bolt is provided 30 for use in case of the breakage of the other bolt.

Intermediate of the catches 19 and 20 is a T-shaped rib 21, which serves as a guide and 35 also to strengthen the joint at the intersection of the two coupling-bars.

At the opposite end each coupling-bar is connected by a universal joint 22 with a box 23, by which it is fastened to the car. This 40 box contains a relief-spring 24, designed to take the jar of the motor-car off the trail-car, and for this reason is adapted to operate both ways. To this end the shank or stem 25 of the outer section of the universal joint extends 45 through said box and is free to slide back and forth therein within fixed limits subject to the tension of the spring 24. Thus the said shank is angular at its inner portion where it passes into the head of the box, 50 (marked 26,) which serves to keep the parts in their proper relation to one another, while at the same time the shank may move a short distance in the head when occasion requires and relieve a sudden start or jar. The remaining 55 portion of the shank is round and extends through the spring 24, a sliding sleeve 27 at the opposite end of the box, outside of which is a nut 28, bearing on the sleeve and serving to secure the end of the shank. It will be seen by a coupling thus constructed 60 and united that the two cars are positively and closely connected and without such play as ordinary couplers, and through which the rear car is constantly jerked back and forth to the great discomfiture of the passengers. This coupling is in a sense rigid, so far as slack is concerned; but by reason of the uni-

versal joints it has all the freedom of play required to give each car its independent movement without communicating the same to the other car. Furthermore, if the motor be started suddenly, the jar to the trail-car is broken by the springs at the opposite ends of the coupling, which will yield sufficiently to take the jar of the trail-car. The same 70 thing will occur if the car be suddenly stopped; but the spring is designed to be strong and firm and not to yield more than is necessary for these special relief purposes. Otherwise it is equal to the strain that comes 80 on the coupling, which it can take without being endangered.

When the coupling is in use, the respective weights of the sleeves 14 will be down, as seen in Fig. 1. This brings the U-shaped portion 85 of the sleeve opposite the slot and opposite the catches 19 and 20, so that the coupling is locked without any danger of becoming unlocked in any ordinary movements of the car. Then to uncouple it is necessary simply to 90 turn the sleeve with the weight directly on top, as seen at the right in Fig. 2, when the bolt 18 is free to slide back into its socket and uncoupling is effected. This is the work of but a moment, as is also the coupling of 95 the parts.

Having thus described my invention, what I claim as new, and desire to secure by Letters Patent, is—

1. A car-coupler having a separate coupling-section for each car and a rotary lock on each section to engage the coupling-bolt, and a coupling-bolt in one section adapted to extend into the other section and provided with lugs engaged by said rotary locks, substantially as described. 100

2. In car-couplers, a tubular coupling-section having a head and a sleeve on the head adapted to turn thereon and provided with a depression at one side for the passage of a locking-lug, and a bolt in the section having two locking-lugs near its center, substantially as described. 110

3. The tubular sectional coupling having a slot along one side, a bolt in the coupling having locking-lugs outside the said slot, and a sleeve on the head of the section to engage said lugs and provided with a weight at one side, substantially as described. 115

4. In a car-coupler, the tubular slotted coupling-sections provided with locking-sleeves, and an independent bolt provided with the lugs 19 and 20 outside of said coupling-sections engaged by said sleeves, substantially as described. 120

5. A car-coupling consisting of two equal sections locked together, each section having a universal joint at its outer end, and a box through which the sections are secured to the car, said box provided with relief-springs, substantially as described. 125

6. The coupling herein described, consisting of two sections, each provided with a locking-bolt and a rotary sleeve on its head to en- 130

gage the bolt, in combination with a universal joint at the outer end of each section, and a box provided with a relief-spring outside the universal joint, substantially as described.

5. 7. The tubular coupling-section having a slot extending lengthwise to its outer end and provided with rings 12 and 13 at said end, in combination with a loose locking-sleeve be-

tween said rings and a bolt engaged by said sleeve, substantially as described.

Witness my hand to the foregoing specification this 21st day of August, 1890.

SOREN ROBERTSON.
